UNITED STATES PATENT OFFICE

IRVING T. BENNETT, OF BROOKLYN, NEW YORK, ASSIGNOR, BY MESNE ASSIGNMENTS,
TO AMERICAN RADIATOR & STANDARD SANITARY CORPORATION, A CORPORATION
OF DELAWARE

HEATING APPARATUS

Original application filed November 16, 1927, Serial No. 233,594. Divided and this application filed February 25, 1930. Serial No. 431,118.

In my application Ser. No. 233,594, filed November 16, 1927, there are described certain radiators and casings or covers therefor and claims are presented based on the casings.

The present application is a division of the aforesaid application and is directed to claims involving features of construction of the radiator in combination with the casing.

10 The radiator may be of different designs. As illustrated herein, it is of the Murray type shown and described more fully in other applications and particularly in a Murray and Bennett application Ser. No. 168,272 filed 15 February 15, 1927, which has now matured into Patent No. 1,790,241 granted Jan. 27, 1931.

In the accompanying drawings, Fig. 1 is a perspective view of an encased radiator;

Fig. 2 is an end elevation of the same showing the wall in vertical section;

Fig. 3 is a perspective similar to Fig. 1, showing another style of casing;

25 Fig. 4 is a vertical transverse section through the radiator of Fig. 3;

Fig. 5 is a perspective of the upper end of the same, with the top of the casing removed;

Fig. 6 is a sectional perspective of an end 30 of the radiator of Fig. 1;

Fig. 7 shows in perspective a steadyng clip.

The Murray radiator is characterized by horizontal, longitudinal heating elements to 35 which is applied a radiating structure forming vertical flues and channels in which the air is heated and a rapid circulation is induced.

In the example illustrated, the heating ele-

The casing may cover the entire radiator including valves and pipes, but preferably it leaves the fittings projecting as illustrated.

The casing is open at levels above the top of the radiator proper for the discharge of heated air and also at levels below the radiator to take in cool air. In the cases illustrated the bottom of the casing is open for admission of air, but the admission opening might be arranged at the front or the ends below the level of the inlet to the radiator flues.

In Fig. 1 there is a front discharge through the upper portion of the front panel and in Fig. 3 the discharge is through the top of the casing.

In Fig. 1 the casing has a closed top wall 5, end walls 6 and a front wall or panel 7 at the upper edge of which is located a perforated plate or grating 8 for emission of the heated air.

The end walls 6 are provided with oblique slots 9 open at the rear edge to permit passing of the latter across a projecting pipe such as the inlet pipe 10. A similar oblique slot at the lower part of the opposite end wall accommodates the outlet pipe 11.

The casing may be long enough to enclose the projecting pipes and fittings. It may also extend clear down to the floor. In fact its proportions may be variously altered. An illustration of such modifications is not attempted, since they do not affect the invention.

According to Fig. 3 the front panel 7 is closed clear to its upper edge and the top 12 is perforated to permit the escape of heated air.

It is assumed in the specific cases illus-

level from the wall and is carried up to the valve 17 which leads to the inlet pipe 10 of the radiator.

The casing is a unitary transportable structure applicable to the radiator after the latter has been installed and adapted to be supported by the radiator; so that, when the latter is suspended above the floor as indicated, the lower edge of the casing may also clear the floor.

The casing may be simply and economically made of sheet metal, such as copper, brass or steel, grained to harmonize with the furniture or woodwork in a room, or painted so as to harmonize with the color of the wall or decorated according to any desired scheme.

In applying the casing to the radiator, nothing more is necessary than to slip it in place by a downward movement over the top 20 of the radiator. It protects the radiator against injury.

The Murray radiators referred to are generally made of extremely thin copper or other sheet metal which is liable to distortion by a slight blow so that a protective casing is particularly useful with this type of radiator. The material and method of production make it possible to manufacture the 30 casing very cheaply.

The top plate 12, Figs. 3 and 4, has a rear flange 18 bent down sufficiently to embrace the rear face of the radiator. End flanges 19 are bent down to fit against the outer faces of the end walls 6. A front flange 20 is bent down and preferably molded into a graceful shape to overlap the front panel 7. The end plates 6 are similarly flanged and bent over to form stiffening moldings 21. And the 40 lower edge of the front panel is formed with a corresponding molding 22. The centre of the front panel may be further ornamented and stiffened as desired.

The top, ends and front panel are readily 45 stamped out and bent to the flanged and molded shapes described. They are then assembled in a jig and spot welded or otherwise firmly jointed. The molding at the lower edge of the panel may be integral with 50 the panel, as in Fig. 4, or a separate strip welded to the sheet as in Fig. 7. The casing is intended to fit fairly closely about the radiator. It should also be held firmly 55 against displacement thereon.

Where a top-discharge of the hot air is 60 permissible, as in the usual location immediately below a window, the casing may rest directly on top of the radiator, as in Fig. 4. Where a front-discharge of hot air is desired, Fig. 6, the top 5 has a depending flange 23 at the back, at the lower edge of which is an angle iron 24, a flange of which projects over the top of the radiator. The angle iron 65 is secured to the plate 23 and may extend along the entire length thereof or may be in

short lengths located at intervals along the plate.

To prevent longitudinal displacement of the casing with relation to the radiator, the front panel 7 has secured to it near its ends, 70 vertical angles 25 (Fig. 5) whose inwardly projecting flanges bear against transverse fins 2 of the radiator. To prevent the lower free edge of the front panel from becoming bulged or otherwise distorted in time, it is 75 preferable to fasten it also to the radiator. This is done by clips, such as are shown in Fig. 7 embracing the edge of the panel and also embracing the lower end of a longitudinal web 3 of the radiating structure. There 80 may be two of these clips, one at each end of the panel, or more, if the panel be of considerable length.

The clip is of spring metal with a hollow 85 central portion 26 adapted to embrace the edges of the parts. An inner flange 27 facilitates introducing it over the web 3. An outer flange 28 is shaped to fit the molding 22 on the panel and to permit the forcing of the clip up over this molding. Thin spacer blocks 29 are introduced between the panel 7 and the web 3 to hold the parts rigidly and at a determined slight distance apart. Or the spacers may be omitted and the clips proportioned so as to clamp the plate 7 90 against the webs 3, as shown for example in Figs. 5 and 6. And, in general, the variations shown in detail in each of the several figures are applicable to the styles of casing 95 shown in each of the other figures. 100

It will be observed that the transverse fins 2 of the radiating structure form alternately flues which are closed by the outer webs 3 and channels which are closed on three sides, but open on the outer side. When the casing is applied, the front panel thereof substantially or approximately covers the outer sides of these channels and converts them into flues closed in cross-section. Such flues have an 105 important function in securing a very rapid heating and circulating effect by the induced draft of the heated air.

Whether the radiator be suspended above the floor or supported thereon, the casing should have its lower edge clear the floor or have openings at or near the bottom for admitting air to the lower ends of the radiator flues and channels. The invention may be applied also to radiators supported by legs 110 resting on the floor. And, however the radiator is supported, the pipes may pass through the floor and directly upward to the valves. 115

The slots in the end walls may be of various other shapes than that shown. For example, they may extend horizontally inward from the edge and then upward. 120

Various other modifications may be made by those skilled in the art without departing 125

from the invention as defined in the following claims.

I claim:

1. A heating apparatus of the character described comprising a radiator having a heating element and a radiating structure of transverse fins connected by webs at their outer edges, a casing separate from said radiator, and means upon the inner wall of said casing engaging the upper end of said radiator for supporting said casing thereon with its top in spaced relation to the upper end of the radiator. 70
2. A heating apparatus of the character described comprising a radiator including a heating element and a radiating structure of transverse fins connected by webs at their outer edges, a casing separate from said radiator, and means arranged upon the rear wall 75 of said casing below the top thereof engaging the upper end of said radiator for supporting said casing thereon with its top in spaced relation to the upper end of said radiator. 80
3. A heating apparatus of the character described comprising a radiator including a heating element and a radiating structure of transverse fins connected by webs at their outer edges, a casing separate from said radiator, and longitudinal supports arranged 85 upon the rear wall of said casing and extending inwardly in a plane below the top thereof and resting upon the upper end of said radiator to provide a space in said casing between the upper end of said radiator and the top of 90 said casing. 95
4. A heating apparatus of the character described comprising a radiator including a heating element and a radiating structure of transverse fins connected by webs at their outer edges, a casing separate from said radiator, and longitudinal supports arranged upon the rear wall of said casing and extending inwardly in a plane below the top thereof and resting upon the upper end of said radiator to provide a space in said casing between the upper end of said radiator and the top of 100 said casing. 105
5. A heating apparatus of the character described comprising a radiator including a heating element and a radiating structure of transverse fins connected by webs at their outer edges, a casing separate from said radiator, and longitudinal supports arranged upon the rear wall of said casing and extending inwardly in a plane below the top thereof and resting upon the upper end of said radiator to provide a space in said casing between the upper end of said radiator and the top of 110 said casing, and vertical stops on the inner side of the casing front for securing said casing against longitudinal movement relative to said radiator. 115
6. A heating apparatus of the character described comprising in combination a heating element, a heat radiating structure applied thereto and a casing, the said heat radiating structure comprising a plurality of flues spaced about said heating element and the said casing cooperating with the spaced flues to form from the spaces therebetween a plurality of additional flues thereby inducing more rapid circulation of heated air through the radiating structure. 120
7. A heating apparatus of the character described comprising a radiator including a heating element and a radiating structure of transverse fins connected by webs at their outer edges, a casing separate from said radiator enclosing the same, means for supporting said casing upon the upper end of said radiator with its top in spaced relation to the upper end of the radiator, and means for securing said casing against longitudinal movement relative to the radiator. 125
8. A heating apparatus of the character described comprising a radiator including a heating element and a radiating structure of transverse fins connected by webs at their outer edges, a casing separate from said radiator, and means upon the inner wall of said casing engaging the upper end of said radiator for supporting said casing thereon with its top in spaced relation to the upper end of the radiator. 130

In witness whereof, I have hereunto signed my name.

IRVING T. BENNETT.
